(57) **CLAIM**

I claim the ornamental design for a wallet, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a front right perspective view of a wallet in the closed position, according to my design;

FIG. 2 is a front elevational view of the wallet of FIG. 1;

FIG. 3 is a rear elevational view of the wallet of FIG. 1;

FIG. 4 is a bottom plan view of the wallet of FIG. 1;

FIG. 5 is a top plan view of the wallet of FIG. 1;

FIG. 6 is a right side elevational view of the wallet of FIG. 1;

FIG. 7 is a left side elevational view of the wallet of FIG. 1;

FIG. 8 is a front perspective of the wallet of FIG. 1, in the open position; and,

FIG. 9 is a rear perspective view of the wallet of FIG. 1, in the open position.

The broken lines shown in the drawings illustrate portions of the wallet that form no part of the claimed design.
